No. 722,720.

PATENTED MAR. 17, 1903.

F. H. LAMB.
CONVEYER CARRIAGE.
APPLICATION FILED DEC. 3, 1902.

NO MODEL.

UNITED STATES PATENT OFFICE.

FRANK H. LAMB, OF HOQUIAM, WASHINGTON.

CONVEYER-CARRIAGE.

SPECIFICATION forming part of Letters Patent No. 722,720, dated March 17, 1903.

Application filed December 8, 1902. Serial No. 133,767. (No model.)

To all whom it may concern:

Be it known that I, FRANK H. LAMB, a citizen of the United States, residing at Hoquiam, in the county of Chehalis, State of Washington, have invented certain new and useful Improvements in Conveyer-Carriages, of which the following is a specification, reference being had therein to the accompanying drawings.

10 This invention relates to a conveyer-carriage, and particularly to a brake mechanism adapted to operate upon a track or way and controlled from a fixed point.

15 The invention has for an object to provide an improved form of brake mechanism adapted to be operated by a system of levers connected to a lever controlled by a line extending to a fixed point.

20 A further object of the invention is to provide an improved construction to permit an adjustment of the brake-shoes to compensate for wear therein and also of an adjustment of the operating links and levers to control the extent of throw of said shoes.

25 Another object of the invention is to provide an improved construction of carriage adapted to receive and support the novel construction of brake mechanism.

30 Other and further objects and advantages of the invention will be hereinafter set forth, and the novel features thereof defined by the appended claims.

35 In the drawings, Figure 1 is a side elevation of the carriage; Fig. 2, a vertical section on the line 2 2 of Fig. 1, and Fig. 3 a detail vertical section showing the means for adjusting a brake-shoe.

40 Like letters of reference refer to like parts in the several figures of the drawings.

45 The letter A indicates the frame of the carriage, which is preferably composed of two parallel members provided at their upper portions with a yoke A', within which carrier-wheels A² are journaled by means of shafts A³, extending between the sides of the frame. These wheels travel upon a track or way of any suitable construction—for instance, a cable A⁴, as herein shown. The invention is herein illustrated as applicable to a cable-way system such as is shown and described in my application filed May 21, 1902, Serial No. 108,404, but is intended to be used in con-

nection with any desired system. For convenience in applying the carriage to the track or way A⁴ one side of the frame is provided 55 with an opening having at each side lugs A⁵, between which a sleeve A⁶ is pivotally mounted by a bolt A⁷ and can be removed when it is desired to place the carriage upon the track.

For the purpose of mounting the brake 60 mechanism supporting-straps B and B' are bolted to the frame at their opposite ends above and below the opening therein, and pivoted to these straps are links B², disposed at an angle to the straps, so as to act 65 as toggles, while at the opposite end of these links a brake-shoe B³ is pivotally secured thereto. One of each of the links above and below the track is provided with an extended lever-arm B⁴, secured thereto and disposed 70 at an angle to the link B², the upper arm being provided with a depending rod B⁵, pivoted to a lever C at the lower portion of the frame, while the lower lever-arm B⁴ is provided with a similar rod or connector B⁶, secured to the pivot C', which also pivots the rod B⁵. The lever C is provided with apertures C², by means of which the pivot C' may be shifted to control the length of throw of the levers, while the lever C is pivoted to the 80 frame at C³ and its outer end C⁴ provided with an aperture C⁵, through which a threaded adjusting-bolt D extends, one end of which bolt being pivotally secured by an eye D' to a pin D², carried by the lever-arm D³, which arm is 85 pivoted at its inner end upon the pivot C³ of the lever C and independently of said lever. The free end of the arm D³ may be operated in any manner and is shown as provided with a sheave or pulley D⁴, over which a line D⁵ extends to a fixed point. The line D⁵ may be the haul-back line used in the system hereinbefore mentioned, or any independent line for the purpose of operating the brake, while the sheave or pulley D⁴ may be of any desired 90 construction—for instance, as shown, where it is provided with a casing D⁶ and with a hinge-joint D⁷, by which said casing may be opened for the purpose of inserting the line upon the sheave. The journal D⁸ of the 95 sheave may be hollow, if so desired, and provided with an oil-cup D⁹ of any desired construction for the purpose of lubricating the bearing of the sheave.

At the lower portion of the frame A a sheave or pulley E is provided and pivotally mounted at E' between the members of the frame A, while the casing E² about the sheave 5 may be provided at one side with a hinge-joint E³ and at the opposite side with a similar joint having a removable pin E⁴, so that the sheave may be swung to one side for the purpose of inserting the line or cable E⁵ thereon. This line or cable may be either the hauling-line shown in the system hereinbefore mentioned or any other desired line for carrying the weight to be conveyed, and the said line is provided with a stop-block E⁶, secured thereto in any desired manner and adapted to engage the lower end E⁷ of the casing of the sheave when the load has been lifted to the proper elevation and by the draft upon the line convey the carriage to the desired point, the strain being upon the surfaces of E⁶ and E⁷.

Above the carrier-wheels A² and between the yokes of the frame suitable oil or grease reservoirs F may be secured, if so desired, and 25 provided with a discharge F', having therein a regulating-valve F² to discharge the lubricant upon the surface of the carrier-wheels, by which it is carried to the cable and also to the journals of said wheels.

30 The threaded bolt D is provided at opposite sides of the end C⁴ of the lever with lock-nuts D⁹, which may be adjusted for the purpose of varying the relation of the end C⁴ to the arm D³, carrying the brake-operating sheave, and the consequent extent of movement of the lever C.

For the purpose of compensating for wear of the brake-shoes and adjusting the same for operation in connection with different characters of track or way the links B² are provided at their upper ends with a head G of any desired configuration—for instance, rectangular, as shown—and at opposite sides thereof with journaling portions G', mounted 45 in the frame B, as shown in Fig. 3, while the extended ends of these heads are threaded at G² and provided with nuts G³, and, if so desired, a cotter-pin G⁴ may be inserted in an aperture beyond the nuts G³. The head G is 50 provided with an aperture therethrough and a threaded bolt G⁵, disposed therein, said bolt being adapted for adjustment in relation to the head by means of nuts G⁶, threaded upon the bolt, while the lower end thereof is 55 provided with a plate G⁷, extending at one side of the brake-shoe B³, and a similar plate at a right angle thereto disposed above the brake-shoe and provided with a projection G⁸, extending through the slot G⁹, formed in 60 the links B². The shoes are clamped to the links and to the adjusting-bolts by means of the shouldered cross-bolt G¹⁰, provided with a nut G¹¹ and extending through the plate G⁷, shoe B³, and slot G⁹, so as to bear upon the 65 face of the link B². It will be seen that the adjusting-bolt being carried by the pivoted head G swings in the movement of the link

B², and by loosening either of the nuts above or below said head the relation of the shoe to the link may be adjusted for any purpose desired. 70

In the operation of the invention it will be seen that when the parts are in the position shown by full lines the brake-operating lever is held in a raised position by the tension upon the line leading thereto, and the carriage may be moved to the desired position upon the track or way. When this position is reached, the line to the brake-sheave is slackened, and the gravity of the line, with the sheave and its connected parts, throws the latter into the position shown by dotted lines in Fig. 1, thus carrying upward the inner end of the lever for operating the links supporting the brake-shoes, throwing said links into a substantially 85 vertical position, whereby the shoes are firmly clamped against the opposite faces of the track, so that the carriage may be controlled when either the brake-line or hauling-line, or both, are slackened and may be braked at any 90 desired point by slackening the brake-line. It will also be seen that the adjusting means for the brake-shoes permit compensation for wear, while the extent of throw or travel of the shoes toward and from the track or way 95 may be varied by the adjustment of the lever operating the same.

It will be obvious that by a reversal of the parts of the brake it can be operated in a movement of the carriage in an opposite direction 100 from that described and by any line attached to the operating-arm and that one of the brake-shoes and its operating-levers and also the sheave upon the brake-arm may be omitted, if found desirable, while the details of construction and configuration may be changed 105 without departing from the spirit of the invention as defined by the appended claims.

Having described my invention and set forth its merits, what I claim, and desire to 110 secure by Letters Patent, is—

1. In a conveyer-carriage, a frame having carrier-wheels journaled therein, a brake-shoe pivotally mounted in said frame by links pivoted at opposite ends to the shoe and 115 frame, means for operating said shoe, and a line extending to a fixed point for operating said operating means; substantially as specified.

2. In a conveyer-carriage, a frame having 120 carrier-wheels journaled therein, a brake-shoe, links extending diagonally to the face of said brake-shoe and pivotally mounted in said frame, a lever for operating said shoe, and a line extending to a fixed point for operating said lever; substantially as specified. 125

3. In a conveyer-carriage, a frame, carrier-wheels pivoted therein, a brake-shoe, a link pivoted at opposite ends to the frame and shoe, a lever-arm secured to the link and extended beyond the pivot thereof, and an operating-lever for oscillating the brake-shoe lever arm and link; substantially as specified. 130

4. In a conveyer-carriage, a frame, carrier-

tion of said frame below the axis of said wheels; substantially as specified.

13. In a conveyer-carriage, a frame, carrier-wheels pivotally mounted therein, a supporting-strap carried by said frame, a brake-shoe, a slotted link pivoted to said shoe and strap, a head disposed upon said link, a bolt adjustably mounted in said head at its upper end and embracing said brake-shoe at its lower end, and a securing device extending through said bolt, shoe and link; substantially as specified.

14. In a conveyer-carriage, a frame, carrier-wheels pivotally mounted therein, a supporting-strap carried by said frame, a brake-shoe, a slotted link pivoted to said shoe and strap, a head disposed upon said link, a bolt adjustably mounted in said head at its upper end and embracing said brake-shoe at its lower end, a securing device extending through said bolt, shoe and link, adjusting-nuts at the opposite sides of said head disposed upon the upper threaded end of the bolt, and a projection from said bolt above the brake-shoe adapted to travel in the slot therein; substantially as specified.

15. In a conveyer-carriage, a frame, carrier-wheels pivotally mounted therein, a brake-shoe mounted upon said frame at its upper portion, an operating-lever having an eye at its outer end and pivoted to the lower portion of the frame to actuate said brake-shoe, an arm pivoted upon the axis of said operating-lever and independently thereof, a threaded bolt having an eye at one end pivoted to said arm, adjusting-nuts upon said bolt at opposite sides of the eye of said operating-lever, and means for oscillating said arm; substantially as specified.

16. In a conveyer-carriage, a frame, carrier-wheels pivotally mounted therein, a brake-shoe mounted upon said frame at its upper portion, an operating-lever having an eye at its outer end and pivoted to the lower portion of the frame, connections therefrom to actuate said brake-shoe, an arm pivoted upon the axis of said operating-lever and independently thereof, a threaded bolt having an eye at one end pivoted to said arm, adjusting-nuts upon said bolt at opposite sides of the eye of

said operating-lever, means for oscillating said arm, means upon the inner end of said lever for adjusting the brake-shoe connections, and a sheave mounted upon the free end of said arm; substantially as specified.

17. In a conveyer-carriage, a frame composed of parallel members one of which is open, lugs upon the frame at each side of said opening, a sleeve pivoted upon said lugs, and carrier-wheels pivoted in said frame above said opening; substantially as specified.

18. In a conveyer-carriage, a frame composed of parallel members one of which is open, lugs upon the frame at each side of said opening, a sleeve pivoted upon said lugs, carrier-wheels pivoted in said frame above said opening, straps extending longitudinally of the frame, and brake-shoes pivotally supported from said straps; substantially as specified.

19. In a conveyer-carriage, a frame composed of parallel members, carrier-wheels pivoted in said frame, brake-shoes pivotally supported from said frame, lubricating-cups disposed between the members of the frame above said wheels to discharge thereon, a sheave supported at the lower portion of said frame, an arm for actuating said shoes; and a sheave carried by said arm; substantially as specified.

20. In a conveyer-carriage, a frame, carrier-wheels journaled therein, a brake-shoe, a supporting-link for said shoe disposed diagonally to the face thereof, and means for oscillating said link toward and from a vertical plane; substantially as specified.

21. In a conveyer-carriage, a frame, carrier-wheels pivotally mounted therein, a track or way, brake-shoes extending between the wheels and disposed upon opposite sides of said track, pivoting-links at the opposite ends of each of said shoes and disposed at an angle thereto and to each other, and means for simultaneously moving said links into a substantially vertical position; substantially as specified.

In testimony whereof I affix my signature in presence of two witnesses.

FRANK H. LAMB.
